US00D849794S

(12) **United States Design Patent** (10) **Patent No.:** **US D849,794 S**
(45) **Date of Patent:** **** May 28, 2019**

(54) **KARAOKE DEVICE**

(71) Applicant: **Shenzhen Teana Technology Co., Ltd.**,
Shenzhen (CN)

(72) Inventor: **Guangguo You**, Shenzhen (CN)

(73) Assignee: **Shenzhen Teana Technology Co., Ltd.**,
Shenzhen (CN)

(**) Term: **15 Years**

(21) Appl. No.: **29/615,385**

(22) Filed: **Aug. 29, 2017**

(51) LOC (11) Cl. **14-03**

(52) U.S. Cl.

USPC **D14/497**; D14/216

(58) **Field of Classification Search**

(57) **CLAIM**

The ornamental design for a karaoke device, as shown and described.

DESCRIPTION

FIG. 1 is a top perspective view of a karaoke device showing my new design;

FIG. 2 is a bottom perspective view thereof;

FIG. 3 is a top perspective view thereof with a broken line portion of the article shown in an alternate position;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top plan view thereof; and,

FIG. 9 is a bottom plan view thereof.

The broken lines show portions of the karaoke device which form no part of the claimed design.

1 Claim, 8 Drawing Sheets
